UNITED STATES PATENT OFFICE.

MARTIN MADSEN, OF MONTEREY PARK, CALIFORNIA, ASSIGNOR TO MADSEN IRON WORKS, OF HUNTINGTON PARK, CALIFORNIA, A CORPORATION OF CALIFORNIA.

MATERIAL DRIER.

Application filed October 11, 1926. Serial No. 140,808.

My invention relates to driers for drying paving and other material in which liquid hydrocarbon or gaseous fuel is used and the object thereof is to produce an efficient drier 5 in the use of which the objectionable dust usually lost in the air and attendant on drying paving material shall be reduced to a minimum.

In the drawings forming a part of this 10 application, Fig. 1 is a fragmentary side elevation, partly in section of my improved sand drier. Fig. 2 is a front elevation of so much of the drier as illustrates my invention.

15 In a suitable frame 5, a portion of which is shown in the drawings, is mounted the revolving drying drum 6 in the rear end of which is received the feed hopper 7 into which the material to be dried is fed in any 20 desired manner. The rear end of drum 6 is higher than the front portion so that as the drum revolves, the material will gradually work its way to the front and pass out through the discharge spout 8. Drum 6 has 25 a gear ring 9 which is engaged by pinion 10 on shaft 11 to which power is applied in any suitable manner to revolve the drum.

Surrounding the front end of drum 6 and spaced therefrom is cowl 12 in the front end 30 of which are the air regulating and inspection doors 13 and 14. These doors are mounted to slide in tracks 15 and 16 and close an opening in the front of the cowl shown in Fig. 2 by dotted line 17. A suitable burner 18 projects into the cowl through 35 the center of the doors. Burner 18 is supplied with liquid hydrocarbon fuel or gaseous fuel through pipe 19 from a supply not shown and with steam or compressed air 40 from a supply not shown through pipe 20.

Within the cowl and projecting into the end of drum 6 is fire box which is lined with fire brick 22. A dust plate 23 has a flange 24 secured thereto which flange projects 45 into the drier 6 in close proximity thereto.

At or near the ends of drum 6 are track

rings 25 which run upon rollers 26. Only one track ring is shown, the other being on the broken out portion. A stack 27 is connected to the end of drum 6 nearest the hopper 7. On the interior of drum 6 are secured longitudinal ledges 28, as the drum revolves carries the material up and drops it.

Paving material that is to be dried is fed into hopper 7 in regulated quantities and 55 slides down into drum 6 which is caused to rotate by suitable power applied to shaft 11. At the same time fuel fed by burner 18 is lighted. The heat soon heats up the walls of drum 6 and as it slowly rotates, the material passing through the drum is caught by ledges 28 and carried up and dropped through the products of combustion. The air to supply combustion passes into the cowl around the fire box so that the dust 65 produced by drying the material is prevented by the air current from coming out of the front end of the drier. By the time the material reaches spout 8 it is thoroughly dried and heated and in proper condition for mixing with the other paving material. Ledges 70 28 could be omitted but I prefer their use as the material dries faster when they are used.

By adjusting doors 13 and 14 a regulated pressure of air is maintained in drum 6. 75

Having described my invention, I claim:

A material drier comprising a frame; a drum revolvably mounted in said frame; a stack mounted in said frame and connected to one end of said drum; a hopper mounted 80 on said frame and discharging into the drum; a cowl surrounding the other end of said drum; a fire box secured to said cowl having open ends, one end projecting into the drum and the other end spaced from the 85 cowl; a discharge chute secured to said cowl; and a burner projecting into the end of the cowl.

In witness that I claim the foregoing I have hereunto subscribed my name this 4th 90 day of October, 1926.

MARTIN MADSEN.
